(57) **CLAIM**

The ornamental design for a control unit for patient lifters as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a top, right side and front perspective view of a first embodiment of the control unit for patient lifters;

Fig. 1.2 is a right side view thereof;

Fig. 1.3 is a rear view thereof;

Fig. 1.4 is a left side view thereof;

Fig. 1.5 is a front view thereof;

Fig. 1.6 is a bottom view thereof;

Fig. 1.7 is a top view thereof;

Fig. 2.1 is a top, right side and front perspective view of a second embodiment of the control unit for patient lifters;

Fig. 2.2 is a right side view thereof;

Fig. 2.3 is a rear view thereof;

Fig. 2.4 is a left side view thereof;

Fig. 2.5 is a front view thereof;

Fig. 2.6 is a bottom view thereof; and

Fig. 2.7 is a top view thereof.

(Continued)

The features covered by a transparent blue overlay depict portions of the control unit for patient lifters that form no part of the claimed design.
